Herbert S. Lenz, Great Neck, N. Y., assignor to R. H. Macy & Co., Inc., New York, N. Y., a corporation of New York

Application September 29, 1938, Serial No. 80,137

Term of patent 3½ years

To all whom it may concern:

Be it known that I, Herbert S. Lenz, a citizen of the United States, residing at Great Neck, in the county of Nassau and State of New York, have invented a new, original, and ornamental Design for Box Cover Paper or Similar Article, of which the following is a specification, reference being had to the accompanying drawing, forming part thereof.

The figure is a plan view of box cover paper or similar article, showing my new design.

I claim:

The ornamental design for box cover paper or similar article, substantially as shown.

HERBERT S. LENZ.
